AWNINGS BRACKET.

APPLICATION FILED SEPT. 12, 1921.

1,429,754.

Patented Sept. 19, 1922.

2 SHEETS—SHEET 2.

UNITED STATES PATENT OFFICE.

FRANCIS MILLER, OF CINCINNATI, OHIO.

AWNING BRACKET.

Application filed September 12, 1921. Serial No. 499,941.

To all whom it may concern:

Be it known that I, FRANCIS MILLER, a citizen of the United States, residing at Cincinnati, in the county of Hamilton and 5 State of Ohio, have invented certain new and useful Improvements in Awning Brackets; and I do hereby declare the following to be a full, clear, and exact description of the invention, such as will enable others 10 skilled in the art to which it appertains to make and use the same.

My invention relates to improvements in awning arrangements for use in applying awnings to windows or other openings, 15 where it is desired to provide a quickly attachable and detachable device which may be readily applied and removed without the use of tools of any kind, and which will operate effectively in conditions of normal use. 20 The invention is more especially intended to provide an arrangement which can be applied to the lower portion of a window opening, and may permit of the opening of the window at the top as well as the bottom to 25 secure better ventilation.

My invention will be more fully understood after reference to the accompanying drawings, in which like parts are indicated by similar reference symbols throughout the 30 several views, and in which:

Figure 1 is a front elevation of a window frame with the two sashes raised and the awning applied below the same, parts being broken away.

Figure 2 is a side elevation of the swinging arms used in connection with the lower portion of the awning, and shows the window frame and the awning and the various other details in dotted lines.

Figure 3 shows a section along the line 3—3 of Fig. 1, and looking in the direction of the arrows; the textile fabric of the awning being removed.

Figure 4 shows a section along the line 4—4 of Fig. 1, and looking down, the textile fabric of the awning being removed.

Figure 5 shows a section along the line 5—5 of Fig. 1, and looking in the direction of the arrows, the parts being shown on a 50 larger scale.

Figure 6 is a similar view to Fig. 5, except that the two cross rods on which the awning proper is mounted are removed.

Figure 7 shows a section along the line

7—7 of Fig. 5, and looking in the direction 55 of the arrows.

Figures 8, 9 and 10 are sectional elevations showing details of the spreader attachment for holding the side frames in place; and Figure 11 is a perspective view of the 60 lower pivot for one of the swinging arms, with means carried thereby for locking the same in place.

Figure 12 is a detail of a slightly modified construction; and

Figure 13 is a section on the line 13—13 in Fig. 12.

A represents the window frame which may be of the usual or preferred construction, and may be either of wood or metal, 70 provided with the two vertical channels α and α' separated by the strip C which may be either separate or integral with the window frame, as preferred.

In Figures 3 and 4 I have shown this 75 strip as integral with the window frame, and the window frame as of metal, but the window frame may be made of wood or other suitable material as desired.

B and B' represents the outer and inner 80 sashes which slide in the channels α and α' , respectively.

D represents one of two side frames adapted to fit in either of the channels α or α' , but preferably in the outer channel α , which 85 frames are held in place under the action of the spreader E, which will be herein-after described. Each of these side frames D preferably comprises a filler D', made of wood or other suitable material. On the 90 side of this filler are two L-shaped plates, bent over and secured to the filler and separated as at d^o , to form a longitudinal slot. Beneath these plates is a channel D^o .

E represents the spreader which is preferably made of two tubular members E' and E², each provided at its outer end with a plug E³, screw threaded at at e to engage in the tubular member, and provided with an outwardly projecting rib e' which engages in 100 the corresponding slot d^o , whereby this spreader E may be conveniently applied at the desired location. The member E² is provided with a screw thread e² which projects into the hand nut E³ which bears 105 against the sleeve e⁴, screwed into the member E' as at e³. By turning the nut E³ the members E' and E² may be spread apart or

drawn together, and thus the requisite pressure may be applied to the opposite side frames D, and the same may be firmly held by friction in the corresponding channels, or 5 by easing up on this nut E³ the pressure may be removed and the frames may be quickly taken out of the corresponding channels.

At the upper end of each of the side frames D I provide a bearing plate F, having 10 a notch f to engage the end i of the rod or roller I. This plate F is held in place by means of the clamp plate G and the bolt H and clamp nut h. Thus this bearing plate may be raised or lowered through a limited 15 distance, relative to the side frames D, so that there may be a space left between the bottom of the sash B and the rod I, as shown in Fig. 7.

Near the bottom of each frame D the 20 swinging arm M is hinged, as by means of the clamp plate P, the bolt O and the clamp nut Q. These arms are preferably made as light as practicable, and for this purpose should be tapered, and provided with ribbed 25 sides m, see Figs. 5 and 6. The outer end of each arm is provided with a notch m', to engage the ends k of the cross rod K, which is held in place by means of the screws N, see Figs. 3 and 4.

30 Spanning the rods I and K are the straps J which may be secured to said rods in any convenient way, as by means of the loops j, see Fig. 5. Secured to these straps J is the awning fabric L which may be of any suitable material, and the edge of this awning may be corrugated or arranged in any suitable way, as indicated in Figs. 1 and 5.

It will be noted that the awning fabric L is normally attached to the rods I and K 40 and may be conveniently removed with the rods and rolled up and put out of the way whenever desired, such, for instance, as when parties are leaving the house, or when a heavy storm is threatening, or the like; 45 but the construction is sufficiently rugged to stand long hard usage. It will also be seen that the arms M may be conveniently attached or removed whenever desired.

In order to assemble the parts, put the 50 frames D in place in opposite channels, put the spreader E in place and press the frames D firmly in engagement with the corresponding channels by turning on the hand nut E³; then mount the rod I, carrying the awning fabric in place, and also the arms M and engage the ends of rod K into the notches m' of the arms M. This may be conveniently done by swinging up the arms to the position shown in Fig. 6, and inserting the ends 55 of the rods K into said notches m' and allowing the said arms to swing down to the position shown in Fig. 5.

It will be seen that the height of the awning may be varied within small limits 60 by raising or lowering the rod I, and the

pitch of the awning may be varied within limits by raising or lowering the inner ends of the arms M.

In order to remove the rods I and K, tilt up the arms M and release the ends of the 70 rod K, take out the rod I and with it the awning fabric and leave the arms M attached to the frames, or separate said arms from the frames D and store them separately. In order to remove the frames, of 75 course, the spreader E must be moved. When stored away, the side frames D and the arms M and the spreader E may be secured in a convenient package and the awning rolled separately, or they all may be 80 rolled up into a single package contained in the awning.

It will be seen that with the arrangement herein described an awning will be provided which will not interfere at all with the 85 vertical movement of the inner sash and will permit the outer sash to be removed a small distance. It will also be seen that the awning is especially arranged to permit of ventilation through the upper and lower portion 90 of the window and to receive light through the upper portion. Moreover, the use of the awning will not in any way interfere with the use of interior roller shades, not shown. 95

Referring to Figs. 12 and 13, the device is here shown as being attached forwardly of the outer window channel by the use of threaded bolts R, passing through the side frames R' and having lugs r fitting into the 100 outer window channel and against the outer channel rib. Winged nuts r' are threaded on the outer ends of the bolts R and take against the outer L-shaped frame members whereby to hold the parts together and 105 against the outer channel rib of the window.

It will be obvious that various modifications might be made in the herein described apparatus, and in the construction, combination and arrangement of parts which could be used without departing from the spirit of my invention; and I do not mean to limit the invention to such details except as particularly pointed out in the claims. 110 115

Having thus described my invention what I claim and desire to secure by Letters Patent of the United States is:—

1. Awning attachments for window frames provided with channels for the sashes, comprising a pair of end frames adapted to fit freely in opposite channels of the window frame, a spreader adapted to spread these end plates apart and hold same in said channels, swinging arms attached to said frames and each provided with a notch on its outer end, notched plates attached to said side frames near the upper end of said frames, a pair of rods adapted to engage in said notched plates and in said swinging 120 125 130

arms, respectively, and an awning fabric extending between said rods.

2. Awning attachments for window frames provided with channels for the sashes, comprising a pair of end frames adapted to fit freely in opposite channels of the window frame, an adjustable spreader adapted to spread these end plates apart and hold same in said channels, or to release same when desired, swinging arms attached to said frames and each provided with a notch on its outer end, notched plates detachably connected to said side frames near the upper end of said frames, a pair of rods adapted to engage in said notched plates and in said swinging arms, respectively, and an awning fabric extending between said rods. 55

3. Awning attachments for window frames provided with channels for the sashes, comprising a pair of end frames adapted to fit freely in opposite channels of the window frame, a spreader adapted to spread these end frames apart and hold same in said channels, swinging arms attached to said frames and each provided with a notch on its outer end, notched plates attached to said side frames near the upper end of said frames, a pair of rods adapted to engage in said notched plates and in said swinging arms, respectively, parallel straps connecting said rods, and an awning fabric secured to said straps and extending between said rods. 60

4. Awning attachments for window frames provided with channels for the sashes, comprising a pair of end frames adapted to fit freely in opposite channels of the window frame, an adjustable spreader adapted to spread these end frames apart and hold same in said channels, or to release same when desired, swinging arms attached to said frames and each provided with a notch on its outer end, notched plates detachably connected to said side frames near the upper end of said frames, a pair of rods adapted to engage in said notched plates and in said swinging arms, respectively, parallel straps connecting said rods, and an awning fabric secured to said straps and extending between said rods. 65

5. Awning attachments for window frames

provided with channels for the sashes, comprising a pair of end frames adapted to fit freely in opposite channels of the window frame, an adjustable spreader extending transversely between said frames and adapted to spread these end frames apart and hold same in said channels, swinging arms detachably connected to said frames near the lower end thereof and each provided with a notch on its outer end, notched plates attached to said side frames near the upper end of said frames, a pair of rods adapted to engage in said notched plates and in said swinging arms, respectively, and an awning fabric extending between said rods. 70

6. Awning attachments for window frames provided with channels for the sashes, comprising a pair of end frames adapted to fit freely in opposite channels of the window frame, an adjustable spreader adapted to spread these end frames apart and hold same in said channels, or to release same when desired, swinging arms detachably connected to said frames near the lower end thereof and each provided with a notch on its outer end, notched plates detachably connected to said side frames near the upper end of said frames, a pair of rods adapted to engage in said notched plates and in said swinging arms, respectively, and an awning fabric extending between said rods. 75

7. Awning attachments for window frames provided with channels for the sashes, comprising a pair of end frames adapted to fit freely in opposite channels of the window frame, an adjustable spreader adapted to spread these end frames apart and hold same in said channels, or to release same when desired, swinging arms detachably connected to said frames near the lower end thereof and each provided with a notch on its lower end, notched plates detachably connected to said side frames near the upper end of said frames, a pair of rods adapted to engage in said notched plates and in said swinging arms, respectively, parallel straps connecting said rods, and an awning fabric secured to said straps and extending between said rods. 80

FRANCIS MILLER.
